UNITED STATES PATENT OFFICE.

ALEXANDER BOYNTON, OF SAN ANTONIO, TEXAS.

CLOSURE FOR TANKS.

Application filed April 9, 1924. Serial No. 705,294.

To all whom it may concern:

Be it known that I, ALEXANDER BOYNTON, a citizen of the United States, and a resident of San Antonio, in the county of Bexar and State of Texas, have invented certain new and useful Improvements in Closures for Tanks, of which the following is a specification.

This invention relates in general to closures for tanks and is particularly designed for use as a closure for the clean out holes of oil tanks.

The object of the invention is to provide a closure of this character which may be applied and removed from the exterior and without the necessity of workmen going into the tank. This feature has special advantages in connection with oil tanks since in such tank the fumes or gases from the oil render it dangerous for workmen to go inside of the tank to place or hold the bolts or other fastening means while the workmen on the outside apply the nuts or other equivalent devices.

A further object is to provide a closure of this character and having these advantages and capacities and which is also of simple and durable construction, reliable and convenient in operation, and adapted to be manufactured at a comparatively slight expense from materials and by means of facilities ordinarily available.

Other objects and advantages of the invention reside in certain novel features of the construction, combination and arrangement of parts which will be hereinafter more fully described and particularly pointed out in the appended claims, reference being had to the accompanying drawings forming part of this specification and in which:

Figure 1 is a top plan view of one embodiment of the invention with one corner of the closure plate broken away for the sake of illustration;

Figure 2 is a view in section on line 2—2 of Figure 1;

Figure 3 is a fragmentary view in perspective of the under side of one corner of the assembly shown in Figure 1, parts being broken away for the sake of illustration;

Figure 4 is a view in bottom plan of one of the channel bars;

Figure 5 is a fragmentary detail view, partly in longitudinal central section and

partly in elevation, showing one end of the channel bar illustrated in Figure 4; and

Figure 6 is a fragmentary perspective view, showing a portion of the casing employed for the channel bars.

Referring to the drawings, it will be seen that the closure which constitutes the present invention contemplates a frame designated generally at 10, the frame being of rectangular form and being made up of pairs of channel bars, designated at 11 and 12 respectively. The channel bars 11 and 12 are of identical construction with the exception that the channel bars 11 have their side flanges cut away or recessed as at 13 to accommodate the channel bars 12. Each channel bar includes a body portion and side flanges. The body portion of each channel bar is formed with a plurality of bolt holes 14.

Bolts, designated generally at 15, are provided and include heads 16 and shanks 17, the heads being fitted in the channels of the bars 11 and 12, as shown in Figure 2, and the shanks 17 projecting through and beyond the bolt holes 14. The bolts 15 are prevented from turning by the engagement of their heads 16 with the side flanges of the channel bars and in order to prevent the bolts 15 from falling from the frame at any time, a casing 18 is provided for each channel bar and is slidably fitted thereon. The casing 18 is in the form of a channel designed to embrace the channel bar to which it is to be fitted, and in the assembly the body portion of the casing 18 extends across the opening of the channel bar with which it is associated. The flanges of the channel casing 18 are formed with inturned portions 19 designed to fit up against the under side of the body portion of the channel bar with which the casing is associated, as shown in Figure 2. The spaces between the inturned portions 19 of the flanges of the casings 18 accommodate the shanks 17 of the bolts 15. Certain of the casings 18 are recessed, as at 20, to accommodate the channel bars.

A closure plate 21 is provided and is formed with bolt holes 22 to accommodate the shanks 17 of the bolts 15. Nuts 23 are threaded on the outer ends of the shanks 17 of the bolts 15 and engage the closure plate 21 to hold the same in position.

With this arrangement the bolts are held fixed and stationary irrespective of whether

the closure plate is applied or removed and even when the closure plate is removed these bolts cannot fall back into the tank. The closure plate may be applied and removed from the exterior and without the necessity of workmen going inside of the tank.

The frame 10 may be secured to the tank structure in any convenient manner as for instance as by means of bolts and nuts 25 10 which coact with the tank structure and with the ends of the channel bars 12.

I claim:

1. A closure of the character described including a rectangular frame made up of 15 channel bars having body portions and side flanges, the side flanges of certain of said channel bars being cut away to accommodate the other channel bars, the body portions of the channel bars being formed with bolt 20 holes, bolts having heads received in the channels of said bars and having shanks

projecting through said bolt holes, a casing for each channel bar, a closure plate having bolt holes accommodating the projecting portions of said bolts, and nuts 25 threaded on the bolts and engaged with said closure plates.

2. A closure of the character described including a rectangular frame made up of channel bars having body portions and side 30 flanges, the body portions of the channel bars being formed with bolt holes, bolts having heads received in the channels of said bars and having shanks projecting through said bolt holes, the heads of the bolts being engageable with the flanges of the channel 35 for preventing turning of the bolts relative to the channel bars, and a casing for each channel bar for preventing the bolts from dropping out of the channel bars.

ALEXANDER BOYNTON.
